(57) **CLAIM**

The ornamental design for an avionics flight display, as shown and described.

DESCRIPTION

FIG. 1 is a right front perspective view of an avionics flight display showing our new design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

The broken lines depicting structural elements have been shown for the purpose of illustrating environment which forms no part of the claimed design.
